BALE TIE

Alvin V. Rowe, Galesburg, Ill.

Application March 21, 1934, Serial No. 716,738

12 Claims. (Cl. 24—27)

This invention relates to bale ties.

One of the objects of the invention is in the provision of a specially formed loop for a bale tie, whereby the loop is enlarged either by folding the wire upon itself, using dual strands of wire, or by providing a seat member with the result that an enlarged gripping surface of a frictional nature is provided for the tie end of the wire.

Another object of the invention is in the provision of a specially formed loop for bale ties which acts in a manner to frictionally grip the tie end of the wire which is passed therethrough.

Still another object is in the provision of a specially formed expanded frictional seat formed in the loop of a bale tie, whereby the tie end of the wire may be seated thereon and frictionally gripped in such manner that the operator has merely the necessity of folding the free end of the wire in a single turn in finally securing the wire to the loop.

Other objects will appear in the following specification taken in connection with the annexed drawing in which

Fig. 1 is a plan view of the invention;

Fig. 2 is a side elevation thereof;

Fig. 3 is an end elevational view;

Figs. 4 and 5 are plan and sectional views respectively of the bale tie showing the shape which it assumes under stress in its assembled arrangement.

Fig. 6 is a view showing a modification of the idea, in which a sheet metal seat is inserted.

Before referring specifically to the drawing, it might be stated that one of the main objections to the old and well known bale tie is the slippage of the tie end of the wire through the loop when secured thereto. This slippage of the wire chafes the wire and thus reduces the gauge and of course the strength thereof.

Applicant has provided a specially formed bale tie which may be constructed of lighter gauge wire but which has a frictional gripping surface in the loop of an expanded nature which absolutely prevents disadvantageous slippage of the wire therethrough.

In the various figures of the drawing, the main wire body portion of the wire is referred to as 10. The loop 11 is formed by folding the wire upon itself in a straight line and thereafter welding the end to the main body portion, as shown at 12. The attachment end of the loop is formed by folding the wire upon itself in the manner shown in the various figures and specifically referred to in the drawing as 13. These loops may

be further secured by means of a welding operation, indicated at 14 and 15.

The wire receiving portion 16 is fashioned to receive the free or tie end of the bale tie 17, it being obvious from a consideration of Fig. 5 of the drawing that a considerable portion of the wire, namely, that portion 18 in the drawing, is held in a frictional manner in the portion 16 of the loop.

As may be clearly seen, the wire is gripped frictionally on either side by the expanded wire portions 13. By this manner of connection a sufficient portion of the wire is actually gripped in the loop that there is absolutely no slippage of the wire and therefore no chafing. As a matter of fact when the loop collapses, the expanded tie wire receiving portions act as levers to clamp the wire therebetween, which prevents slippage of the straight end of the wire therethrough.

As previously explained, this permits a lighter gauge wire to be used with consequent saving in weight and expense. Again, it will be noted that the free end 19 of the wire is so satisfactorily gripped in the loop that the operator has merely to make a very slight twist 20 of the wire about the tie end 17 to effect the final securing of the wire tie about the bale.

A modification of applicant's gripping mechanism is shown in Fig. 3 in which a loop 21 of wire of small gauge is used, the same being welded to the main body portion in the manner previously described. Secured in the receiving portion of the loop is a seat member 22 of an expanded nature. This design shows a bale tie that may be produced at possibly somewhat less cost but one which still has the advantages inherent in the other type shown in the other figures of the drawing.

In this instance, the wire of course is drawn through the friction seat in the exact manner before described, and is twisted back upon itself with a single twist. In exactly the same manner, when a strain is placed upon the tie, the seat frictionally grasps a considerable portion of the wire, as indicated in the other figures and with exactly the same advantages.

What I claim is:

1. A bale tie having a loop, and a straight wire portion connected therewith, said loop being fashioned with an expanded tie wire receiving seat comprising a loop section having lateral portions thereon secured together as a unit to form a reinforced loop section which operates to grip the wire under stress in a frictional manner and

- prevent slippage with consequent chafing of the wire.
2. A bale tie having a fixed loop, a straight wire portion, said loop being fashioned with an auxiliary expanded seat portion which operates to grip the tying end of the straight wire under stress in a frictional manner to prevent slippage therethrough.
3. A bale tie having a loop and a straight wire portion, said loop being fashioned with an expanded seat portion comprising a loop section having lateral portions thereon secured together as a unit to form a reinforced seat portion operating to grip the wire under stress in a frictional manner and prevent slippage of the tying end of the straight wire therethrough.
4. A bale tie having a loop and a straight wire portion, said loop having a unitary, fixed tie wire receiving portion which operates to grip the wire under stress in a frictional manner and prevent slippage of the tying end of the straight wire therethrough, said gripping portions of the stock being greater in cross section than the remaining portions of the loop stock.
5. A bale tie including a main length of tie wire, and a plurality of relatively fixed superimposed bent sections at one extremity thereof providing a loop for receiving the tying end of said main length, the surfaces of said fixed sections cooperating to frictionally grip said tying end in a manner to prevent slippage thereof.
6. A bale tie including a main length of tie wire, and a plurality of superimposed bent sections at one extremity thereof secured together to prevent relative movement therebetween providing a loop for receiving the tying end of said main length, the surfaces of said fixed folds cooperating to frictionally grip said tying end in a manner to prevent slippage thereof, said folds being welded together whereby to prevent relative movement of the folds when the tying wire is tightened therein.
7. A bale tie including a main length of tie wire, and a plurality of superimposed bent sections at one extremity thereof having their engaging surfaces secured together providing a loop having a restricted and enlarged area for receiving the tying end of said main length, the surfaces of said fixed folds cooperating to frictionally grip said tying end in a manner to prevent slippage thereof.
8. A bale tie including a main length of wire, wire receiving means at one extremity thereof having an opening and including wall sections surrounding the opening thereof for receiving the opposite extremity of the wire, said wire receiving means having a wall section spaced from the main length of wire of greater cross-sectional area than the wall section of the receiving means immediately adjacent the main length of wire.
9. A bale tie including a main length of wire
- having a free end, wire receiving means at one extremity thereof having an opening and including wall sections surrounding the opening thereof for receiving the opposite extremity of the wire, said wire receiving means having a wall section spaced from the main length of wire of greater cross-sectional area than the wall section of the receiving means immediately adjacent the main length of wire, and presenting a crotch-like structure for frictionally gripping the free end of a main length of wire.
10. A bale tie including a main length of wire having a free extremity, a loop formed at the opposite extremity thereof, the end of the loop wire being secured to said main length of wire, said loop at its outer extremity being reinforced to provide a greater cross-sectional stock area than the remaining portion of the loop stock, said loop being constructed and arranged for the reception of the free end of said main length of wire, whereby to permit said free end to yield and seat itself against said reinforced portion of the loop, said reinforced portion having a wire receiving contour presenting increased contactual surface area to facilitate frictional resistance between said reinforced portion and the free end of the main length of wire when the bale tie is under tension.
11. A bale tie including a main length of wire having a free extremity, a loop formed at the opposite extremity thereof, the end of the loop wire being secured to said main length of wire, said loop at its outer extremity being reinforced to provide a greater cross-sectional stock area than the remaining portion of the loop stock, said loop being constructed and arranged for the reception of the free end of said main length of wire, whereby to permit said free end to yield and seat itself against said reinforced portion of the loop, said reinforced portion presenting a crotch-like construction presenting increased contactual surface area to facilitate frictional resistance between said reinforced portion and the free end of the main length of wire when the bale tie is under tension.
12. A wire bale tie including a length of wire having a free extremity and a tie loop provided at the opposite extremity thereof, said loop including wall sections embracing an opening of restricted size and a communicating opening of larger size, for receiving the free end of said main length of wire, the wall section in the vicinity of said restricted opening being of greater cross-section than remaining wall sections of the loop, and adapted when the free end of the wire is seated therein and a pulling force is exerted upon the wire, to frictionally grip said free end to prevent slippage thereof through said restricted opening.
